UNITED STATES PATENT OFFICE.

JAMES J. DESMOND, OF SOUTH NORWALK, CONNECTICUT.

HAT.

Application filed June 17, 1926. Serial No. 116,564.

The present invention relates to improvements in hats, especially stiff straw hats, an object being to provide a hat of this character having a flexible head conforming portion between the crown and the brim, whereby the hat will readily conform to and comfortably fit the head of the wearer, without the necessity for blocking or reshaping.

It is particularly proposed to provide a flexible area formed of straw braid of relatively greater flexibility than that of the crown and brim of the hat, and so constructed and arranged that the exposed right or finished edges of the braid will be toward the outer edge of the brim, and at the same time will be so secured, by stitching, that gaping open of the overlapped braid is prevented. The hat will therefore maintain its smooth unbroken surface and attractive appearance under all conditions of use. The method of stitching the braid is also adapted to give increased flexibility and strength to the hat structure, and is furthermore such that it will blend into the braided structure in a manner as to be practically invisible.

With the above and other objects in view, an embodiment of the invention is shown in the accompanying drawings, and this embodiment will be hereinafter more fully described with reference thereto, and the invention will be finally pointed out in the claims.

In the drawings:—

Fig. 1 is a perspective view of a straw hat, according to the present embodiment of the invention, a portion of the band being broken away;

Fig. 2 is a diagrammatic sectional view of a portion of the crown and the brim, before sizing and pressing;

Fig. 3 is a similar view, after sizing and pressing;

Fig. 4 is an enlarged elevation of a portion of the crown braid, and an adjacent portion of the flexible braid portion;

Fig. 5 is a diagrammatic sectional view, enlarged of the flexible portion, and adjacent portions of the crown and brim;

Fig. 6 is a perspective view of the stitching, as employed in the crown and brim; and

Fig. 7 is a perspective view of the stitching as employed in the flexible portion.

Similar reference characters indicate corresponding parts throughout the several figures of the drawings.

Referring to the drawings, the straw hat,

according to the present embodiment of the invention, comprises a crown 10, the straw braid of which is arranged and stitched in the usual manner, the stitching 11, for this purpose, being shown as of the invisible single thread type. As shown in Figs. 4 and 6 the connecting triple strands 11^a are at the under surface and the spaced double tacking portions 11^b are stitched through the under portion of one winding of the braid and through the overlapped edge of the superimposed winding. The side of the crown is completed in this manner to a point spaced from the brim, and thereupon the flexible portion or area 12 is stitched in, this portion completing the side of the crown to the plane of the brim, and being then continued outwardly in flatwise relation to a point calculated as sufficient to provide a flexible head conforming area.

The portion 12 is formed of straw braid of relatively greater flexibility than that of the crown, and is wound and overlapped in a similar manner, that is, with the right or finished edges downwardly in the crown and outwardly in the brim. The stitching 13 for securing the braid of the portion 12 is of zig-zag single thread type, the double loop strands 13^a being at the under side and the single zig-zag strands 13^b being at the upper side of the overlapped braid. This type of stitching is clearly illustrated in Fig. 7. In order to prevent gaping open of the stitched braid, the forward points 13^c of the thread are passed through the lower winding of the braid outside of the edge of the overlapped upper winding, preferably between the points of the braid edge where a pointed edge braid is employed, the rearward points 13^d being passed through both windings. The overlapped edge is thus securely closed, and any possibility of its gaping open, either from flexing, bending, or otherwise forcing the structure out of its natural shape, is entirely prevented. This manner of stitching furthermore reinforces and strengthens the structure of the flexible area, and increases its flexibility through its capacity to give in all directions.

The first winding of the upper layer of the brim 14 is secured to the edge of the flexible portion 12 by the zig-zag stitch 13, and is then completed to the outer edge with the invisible stitching 11. The under layer 15 of the brim is secured to the upper layer 11^a at the outer edge, and at a point in sub-

stantial register with the outer edge of the flexible portion 12 a flexible portion 16 is stitched in by the zig-zag stitches 13 and continued inwardly to complete the under 5 layer of the brim. The right or finished edges of the portion 16 are outwardly toward the outer edge of the brim.

The hat is completed by sizing and pressing, as shown in Fig. 3, the crown and brim 10 being sized in the usual manner to produce a relatively stiff hard structure, while the flexible portions 12 and 16 are either left unsized, or sized sufficiently to give them a proper body, and render them moisture 15 resisting, without destroying their inherent flexibility.

Obviously any suitable styles of braid may be employed, and the flexible area may be of any desired dimensions, extending 20 entirely over the crown, or brim, or both. The improved method of securing the edge of the overlapped braid by means of overlying stitches, the stitches at the same time firmly securing the superimposed windings 25 of braid, provides a straw hat structure of very attractive appearance, extremely flexible, and at all times presenting a smooth, unbroken, non-gaping surface.

I have illustrated and described preferred 30 and satisfactory embodiments of the invention, but it will be obvious that changes may be made therein, within the spirit and scope thereof, as defined in the appended claims.

Having thus described my invention, what I claim and desire to secure by Letters Pat- 35 ent is:—

1. In a hat, of straw or the like, a crown, a brim, and a flexible section extending into the crown and brim and composed of a circumferentially-wound overlapped braid, a 40 stitching for securing the circumferential windings of the braid to one another, said stitching comprising stitches overlying the top outer finished edge of the windings and extending into the adjacent underlying 45 windings whereby to avoid gaping between the superposed windings at the right edges.

2. In a hat, of straw or the like, a crown, a brim, and a flexible section extending into the crown and brim and composed of a circumferentially-wound overlapped braid, flexible stitching for binding said windings of the braid together, said flexible stitching comprising stitches overlying the outer finished edge of the windings and extending 50 into the adjacent underlying braid windings to avoid gaping of the outer finished edge, said stitches extending in a zig-zag path circumferentially over the outer finished edge whereby to secure both circumferential and 55 radial relative movement and flexibility in the braid windings of said section.

Signed at Bridgeport, in the county of Fairfield, and State of Connecticut, this 15th day of June, 1926.

JAMES J. DESMOND.
